UNITED STATES PATENT OFFICE

MARRETT F. MA REAN, OF KANSAS CITY, MISSOURI, ASSIGNOR OF ONE-HALF TO ELBERT A. TAYLOR, OF KANSAS CITY, MISSOURI

TAPERED TOOTH CLIPPER

Application filed May 24, 1930. Serial No. 455,252.

This invention relates to hair clippers and presents as its primary object a point of invention which might be built into the hair clipping device as it is manufactured, or 5 which may be made a part thereof by alteration or attachment after the clipper has been in use.

One of the objects of the invention is to provide a hair clipper especially constructed 10 to form a feather edge at the hair line through the use of clippers only and without the use of other instruments which prolong the operation.

It is well known in this art that during the 15 process of cutting hair two sets of hair clippers, or two sets of blades of varying fineness must be used in connection with the final operation of feather edging through the use of barber's shears before the hair line is satisfactorily formed. It is therefore an object 20 of this invention to provide hair clippers or attachments therefor which will have the qualification of supporting the cutting blade of the same in a position with respect to the 25 base of the hair along the hair line which will cut the same in varying lengths, such variation being gradual and progressive to preclude objectionable steps or ragged appearance.

With the above major objections of this 30 invention in view and bearing in mind the many modifications which might be followed in practicing this invention, the same will be described by reference to the accompanying 35 drawing wherein;

Figure 1 is a top plan view of a hair clipper having a ledger plate made in accordance with this invention.

Fig. 2 is a fragmentary side elevation of 40 the clipper shown in Fig. 1.

Fig. 3 is a vertical cross section through the ledger and cutting plates of the hair clipper shown in Fig. 1, taken on line III—III of said figure, and

Fig. 4 is an enlarged, fragmentary, side elevation of the nose portion of the clipper, viewing the opposite side of the clipper from the side illustrated in Fig. 2.

With particular reference to the form of 50 the invention shown in the accompanying

drawing wherein like reference numerals refer to similar parts shown in several views, 4 indicates an ordinary hair clipper which has been diagrammatically shown for purposes of illustrating the invention. Manifestly, the improvement contemplated by this 55 invention might be applied to any form of hair clipper with equally efficient effect.

The length to which the hair is cut depends upon the thickness of the teeth 6 formed by the ledger plate 8 which is supported in a stationary condition by the clipper 4. The lower edges of the series of teeth 6 indicated at 10 presents the surface which rides over the skin when the clipper is in use. 60 This surface 10 is disposed at an angle with respect to the opposite faces of the teeth 6 upon which rides the lower face of the cutting plate 12 which is also provided with outwardly projecting teeth 14. The angularity 65 of surface 10 causes teeth 6 to be thicker at their base than at their free ends and the sides of teeth 6 converge as the lower edge is approached.

The ends of teeth 14 and teeth 6 of the cutting and ledger plates 12 and 8 respectively terminate in straight alinement and, as well known in the art, rapid reciprocation on the part of plate 12 cuts the hair as it projects between the series of teeth formed on each 70 of the plates mentioned.

Lower faces 10 of teeth 6 of ledger plate 8 angle upwardly toward the free ends of the teeth from a common line which is parallel to the front edge of said ledger plate. Each 75 angle of the lower faces of teeth 10 is progressively greater as one side of ledger plate 8 is approached from the opposite side thereof. In Fig. 3 of the drawing the angle of inclination becomes greater as the right side 80 is approached from the left. In other words, the end tooth 6 at the left of Fig. 3 is the same thickness as ledger plate 8. This tooth 6 is shown in side elevation in Fig. 2 while the bottom of tooth 6 at the other end is indicated 85 by the dotted line in this figure.

In forming a feather edge along the hair line, it is desired that the hair at the edge of the line be shorter and that the length thereof progressively increase as the distance inward. 90

ly from the hair line is made greater. Since teeth 6 are progressively graduated in thickness, it is readily seen that running the clippers 4 along the hair line with the thinnest teeth adjacent the edge of the hair line, the feather edge effect will be created in one operation.

Ordinarily ledger plates may be replaced by plates embodying this invention and clippers may be provided with the improvement during the manufacture of the same. It has been found in practice that the time of cutting hair is appreciably decreased when using a clipper embodying this invention and since the same might be incorporated in separately sold ledger plates, it is desired also to point out the advantage of the invention as incorporated in a new article of manufacture.

The preferred form of the invention has been described herein and the accompanying drawing clearly illustrates the principle involved and, since various materials may be used, various sizes of the device created and modifications of many characters practiced, it is desired to be limited only by the scope of the appended claims.

Having thus described the invention, what is claimed as new and desired to be secured by Letters Patent is:

30. 1. In a hair clipper, a reciprocable cutting plate including a plurality of spaced teeth, and a stationary ledger plate having a plurality of spaced teeth to coact with the cutting plate teeth, and adjacent sides of each set of teeth being in frictional engagement when the cutting plate is reciprocated with respect to said ledger plate, the remote sides of each set of teeth being inclined with respect to the adjacent sides, the said inclination extending from each tooth point to the connection thereof with the respective plate, the inclined sides of said teeth meeting at an acute angle at the points thereof, said ledger plate teeth progressively increasing in angularity as one side of said plate is approached from the other, the bases of all of said ledger plate teeth being on a common line equidistant from and parallel to the front edge of said plate.
50. 2. In a hair clipper, a reciprocable cutting plate including a plurality of spaced teeth, and a stationary ledger plate having a plurality of spaced teeth to coact with the cutting plate teeth, the adjacent sides of each set of teeth being in frictional engagement when the cutting plate is reciprocated with respect to said ledger plate, the remote sides of each set of teeth being inclined with respect to the adjacent sides, the said inclination extending from each tooth point to the connection thereof with the respective plate the connections of all teeth with the plate being on a common line parallel to the ends of said teeth, the inclined sides of said teeth meeting at an acute angle at the points there-

of, said ledger plate teeth progressively increasing in angularity from one side of said plate to the other, the points of all of said teeth of the clipper terminating in alinement equidistant from the common line of connection of teeth and respective plates, each ledger plate tooth having its opposite sides converging as the lower edge is approached, the angle of convergence of each tooth being different in accordance with the tooth angularity whereby a lower edge of like width is formed on each of said ledger plate teeth.

3. As a new article of manufacture, a ledger plate for hair clippers, having a series of equally spaced teeth terminating in straight alinement equidistant from said plate, the lower edge of each tooth being inclined rearwardly from the point thereof to its point of attachment with said plate said teeth joining said plate on a common line parallel to the ends thereof, the upper and lower edges of said teeth meeting at an acute angle, each tooth also having the sides thereof converging as the lower inclined edge is approached, the angle of convergence of each tooth being different in accordance with the angle of inclination of the respective tooth whereby to present a lower edge of like thickness on each tooth.

4. In a hair clipper, a movable cutting plate; a stationary ledger plate associated with said cutting plate; and a plurality of spaced apart teeth formed by said ledger plate, the lower face of each tooth being angled upwardly from the bottom face of said plate from a common line, said line being parallel to the front edge of the said ledger plate, each angle of the lower faces being progressively greater or smaller from one side of the ledger plate to the other.

5. In a hair clipper, a movable cutting plate; a stationary ledger plate associated with said cutting plate; and a plurality of spaced apart teeth formed by said ledger plate, the lower face of each tooth being angled upwardly from the bottom face of said plate from a common line, said line being parallel to the front edge of the said ledger plate, each angle of the lower faces being progressively greater or smaller from one side of the ledger plate to the other; the sides of each tooth of said ledger plate converging toward each other as the lower inclined face thereof is approached, the angle of convergence of each tooth being different in accordance with the angle of inclination whereby to present a plurality of ledger plate teeth having lower faces of like width but of different angle of inclination.

In testimony whereof, I hereunto affix my signature.

MARRETT F. MA REAN.
